UNITED STATES PATENT OFFICE.

CHANDLER I. YONGE, OF TAMPA, FLORIDA.

DESIGN FOR A TOOL-HEAD.

SPECIFICATION forming part of Design No. 34,663, dated June 11, 1901.

Application filed May 14, 1901. Serial No. 60,246. Term of patent 14 years.

To all whom it may concern:

Be it known that I, CHANDLER I. YONGE, a citizen of the United States, residing at Tampa, in the county of Hillsboro and State 5 of Florida, have invented and produced a new and original Design for Tool-Heads, of which the following is a specification.

My invention relates to a new and original design for tool-heads, and is illustrated in the accompanying drawings, in which—

Figure 1 is a perspective view, and Fig. 2 a side elevation.

The leading feature of my design resides in a tool-head formed with a longitudinal socket and having extending from the front face thereof a solid projection, the rear of the tool-head being formed with a series of pairs of arc-shaped fingers, the outer and longest pair inclosing the other pairs, which are arranged within the space between said longest pair and the solid part of the tool-head.

In the said drawings the reference-numeral

1 indicates the tool-head having a socket 2 and provided with a solid projection 3, extending from the front face thereof. The 25 rear of the tool-head is formed with a series of pairs of arc-shaped fingers 4 5 6, the outer pair of which is the longest and incloses the other pairs which, are arranged within the space between said outer and longest pair of 30 fingers and the solid portion of the tool-head.

My design presents a tool-head of novel, pleasing, and distinguished appearance.

Having thus described my invention, what I claim is—

The design for a tool-head substantially as herein shown and described.

In testimony whereof I have hereunto set my hand in presence of two subscribing witnesses.

CHANDLER I. YONGE.

Witnesses:

EDWARD L. SPARKMAN,
GEO. H. WILDER.
